CONTROL AMPLIFIER

Edward W. Kellogg, Indianapolis, Ind., assignor
to Radio Corporation of America, a corporation
of Delaware

Application October 14, 1941, Serial No. 414,914

8 Claims. (Cl. 179—171)

This invention relates to a control amplifier of the type used particularly in controlling ground noise reduction apparatus in sound recording. This type of amplifier is also useful in controlling other apparatus such, for example, as volume controls, compressors, expanders, and the like.

The present apparatus is an improvement on that described and claimed in the application of Barton Kreuzer, Serial No. 263,866, filed March 24, 1939, now Patent No. 2,260,717 and entitled "Sound recording system."

The said Kreuzer application describes a ground noise reduction amplifier having two parallel channels, one of which is operative at low amplitudes and has a high amplification, while the other channel is operative at higher amplitudes and has a low amplification. The advantage of such an arrangement is that, when a sound begins or when a very low sound suddenly increases, the ground noise reduction shutters or equivalent apparatus is moved rapidly, thereby avoiding the clipping of peaks on short sounds or on rapidly increasing sounds; while, at higher amplitudes, the ground noise track is kept just sufficiently clear of the sound wave peaks without the excessive clearance and consequent ground noise which would result if the initial amplification were used over the entire recording range.

The present apparatus, like the Kreuzer apparatus, uses two channels but differs therefrom in that the high amplification channel is definitely limited in its range of operation and is provided with a much more rapid timing circuit than the other channel.

One object of the invention is to provide a control amplifier;

Another object of the invention is to provide a ground noise reduction amplifier which will respond more promptly to impulses of low amplitude;

Another object of the invention is to provide a control amplifier having rapid timing at low amplitudes and slower timing at high amplitudes.

Other and incidental objects of the invention will be apparent to those skilled in the art by a reading of the following specification and an inspection of the accompanying drawing in which

Figure 1 is a characteristic curve of the amplifier showing the relation between signal voltage and opening of the ground noise reduction

shutter, or the operation of similarly controlled apparatus;

Figure 2 is a schematic wiring diagram of one form of my improved amplifier;

5 Figure 3 shows a modified form thereof, differing slightly from Figure 2; and

Figure 4 shows a form corresponding to Figure 2 but using a full wave rectifier.

In Figures 2 and 3 similar parts are indicated 10 by the same reference numerals.

In the form of the invention shown in Figure 2, the audio frequency input to the amplifier, which is usually the output of a voltage amplifier or of the recording amplifier, is fed to the apparatus through the transformer 10, which is provided with two secondary windings. The output from the transformer 10 is applied to the rectifier 11, which is of the type normally used as a full wave rectifier. It will be noted 15 that, in the present instance, the two portions of the rectifier are used to rectify the same half wave instead of opposite half waves, as is more customary. The output from the lower secondary of the transformer 10 is fed through the lower portion of the circuit, which is constructed 20 in the manner now customary for ground noise reduction amplifiers. The output of the rectifier is filtered by the capacitors 13 and 15 and the resistor 14, the capacitors being shunted by the resistor 12. The output from this filter circuit is used to control the amplifier tube 16, the 25 output of which is used to control the ground noise reduction apparatus or other device to be controlled and indicated at 17. In this filter circuit, the charging time of the capacitor 13 is determined by the internal resistance of the rectifier 11, the resistance of the secondary of the transformer 10, and the value of the resistor 12; while the charging time of the capacitor 15 is 30 determined by these factors and also the value of the resistor 14. The discharge of the capacitor 15, which merely controls the grid potential in the tube 16, is determined by the rate of discharge of the capacitor 13 through the resistor 12 and the discharge of the capacitor 15 through the resistors 14 and 12 in series. The timing of 35 this portion of the circuit may be substantially the same as that of the ground noise reduction circuits ordinarily used in the art.

40 The output of the upper secondary of the transformer 10 is used to control the output of the tube 25 and is passed through an entirely different timing circuit. The output from the upper secondary of transformer 10 may be at a 45 considerably higher voltage than that of the low-

er secondary, or the output voltage of the rectifier 11 from this portion of the transformer secondary may be amplified by the tube 19. This portion of the circuit provides the high speed and high gain initial opening shown in the portion A of the curve of Figure 1. Since this portion of the circuit works only over the lower portion of the sound recording amplitude, it is not necessary that it should have as effective filtering as the lower portion of the circuit, and the timing of this portion of the circuit may, accordingly, be speeded up by reducing the filtering. The output from the upper secondary of the transformer 10, after being rectified, is, accordingly, filtered only by the capacitor 18 shunted by the resistor 29, and these elements may be of such dimensions as to give a much more rapid response than the filter circuit 12, 13, 14, 15. The portion of the output of the rectifier filtered by 29 and 18 is applied to the grid of the tube 19, which is an ordinary triode, as shown. This tube has a relatively low plate voltage, for example of the order of 20 volts, applied to it through the resistor 21, the grid bias voltage being determined by the resistor 20. Instead of the output of this tube being taken from the plate, as usual, use is made of the drop across the resistor 20, which is a relatively large portion of the applied plate voltage. This voltage is applied through the resistor 22 and the battery 24 to the grid of the tube 25. Any other appropriate bias means may be substituted for the battery 24, as, for example, a battery shunted by a potentiometer, or one of the customary sources of rectified and filtered alternating current. The filtering for the initial opening of the device 17 is determined by the values of the resistor 22 and the capacitor 23 and is made considerably faster than the timing of the lower filter circuit, first described. Since the maximum possible jump in voltage across the resistor 20 is limited to a predetermined magnitude by the plate voltage applied to the tube 19, the maximum rate of change of voltage across the capacitor 23 is limited and, if the values are properly chosen, this will ensure that the initial opening circuit cannot cause shutter thump no matter how much gain is used in the upper secondary of the transformer 10 or in the tube 19. Tests have shown that the audibility of the opening of the shutter or other ground noise reduction apparatus is determined by the rate of change of shutter current. It may be desirable to give the filter circuit 29, 18 a faster rate of discharge than the circuit 12, 13.

It will be apparent to those skilled in the art that any or all of the various resistors shown in this circuit may be made adjustable, if desired, so that the timing may be adjusted to the best value for the particular type of recording being done at any particular time.

The relatively poor filtering in the circuit 17, 18 is no disadvantage at higher amplitudes since, as shown in Figure 1, the tube 19 cuts off at the top of the portion A of the curve, and the impulses which may not be adequately filtered in the filter circuit are not transmitted therethrough.

The form of the invention shown in Figure 3 is substantially identical with that shown in Figure 2 with the exception that an inductance 28 is substituted for the resistor 14 in the main timing circuit, and the resistor 12 controlling the discharge time of the capacitor 15 is moved to shunt the capacitor 15 instead of the capacitor 13. This arrangement will permit different ratios

of opening and closing times to be secured in the main timing circuit than can be secured by the arrangement shown in Figure 2.

It will be apparent that either or both of the rectifiers which charge the condensers 13 and 18 may be of the full wave type instead of half wave rectifiers as shown in Figs. 2 and 3. In general, it is desirable that the quick acting, limited amplitude circuit comprising elements 18, 19, 29 in the figures, be charged through a full wave rectifier 28, since this results in producing the small initial opening as soon as a wave of either polarity arrives at the input of the system, whereas with a half-wave rectifier, nothing happens until a wave of certain polarity arrives. Such an arrangement is illustrated in Fig. 4 which is in other respects identical with Fig. 2.

I claim as my invention:

1. An amplifier of the class described having 20 independent parallel electrical channels between the input and output thereof, one of said channels being effective at low amplitudes only and having relatively fast timing, and the other channel being effective at higher amplitudes and having 25 slower timing.

2. An amplifier of the class described having independent parallel electrical channels between the input and output thereof, one of said channels being effective at low amplitudes only and 30 having relatively fast timing and filtering circuits, and the other channel being effective at higher amplitudes and having slower timing.

3. An amplifier of the class described having independent parallel electrical channels between 35 the input and output thereof, one of said channels being effective at low amplitudes only and having relatively fast timing and filtering, and the other channel being effective at higher amplitudes and having slower timing and more 40 effective filtering.

4. An amplifier of the class described having independent parallel electrical channels between the input and output thereof, one of said channels being effective at low amplitudes and having 45 a relatively sharp output limit at a predetermined amplitude, and having relatively fast timing, and the other channel being effective at higher amplitudes and having slower timing.

5. An amplifier of the class described having 50 independent parallel electrical channels between the input and output thereof, one of said channels being effective at low amplitudes only and having relatively fast timing and high amplification, and the other channel being effective at higher amplitudes and having slower timing and less amplification.

6. An amplifier of the class described having independent parallel electrical channels between the input and output thereof, one of said channels being effective at low amplitudes only and having a relatively sharp cut-off at a predetermined amplitude, relatively fast timing and high amplification, and the other channel being effective at higher amplitudes and having slower timing and less amplification.

7. An amplifier of the class described having independent parallel electrical channels between the input and output thereof, one of said channels having a limited output and high amplification, whereby its output limit is attained with 70 relatively low signal input, and the other channel being capable of higher output, but having lower gain, both of said circuits being provided with filters which cause a time lag between input and output, the filter for said limited ampli-

tude circuit being designed for less time lag than the filter for said lower gain circuit.

8. An amplifier of the class described having independent parallel electrical channels between the input and output thereof, one of said channels being effective at low amplitudes only and having a relatively sharp cut-off at a predeter-

mined amplitude, relatively fast timing and high amplification and including a full wave rectifier, and the other channel being effective at higher amplitudes and having slower timing and less amplification.

EDWARD W. KELLOGG.
